FLASHING SIGNAL LIGHT

Peter T. Quinn, Littleton, Colo., assignor to
Honeywell Inc., Minneapolis, Minn.

Filed Sept. 12, 1974, Ser. No. 505,760

Term of patent 14 years

Int. Cl. D10—06

U.S. Cl. D10—114

FIG. 1

FIG. 2

FIG. 1 is a front perspective view of a flashing signal light showing my new design; and

FIG. 2 is a rear perspective view of the flashing signal light shown in FIG. 1.

I claim:

The ornamental design for a flashing signal light, as shown.
